HANDLE FOR A STORM WINDOW INSERT

Edwin R. Thompson, Canfield, Ohio, assignor to Western Reserve Plastics, Inc., Canfield, Ohio

Continuation of applications Ser. No. 65,491, June 6, 1961, and Ser. No. 65,492, June 6, 1961. This application Jan. 17, 1962, Ser. No. 68,617

Term of patent 14 years

(Cl. D10—10)

FIG. 1

FIG. 2

FIG. 3

FIG. 4

FIG. 5

FIG. 6

FIG. 7

FIG. 8

FIGURE 1 is a perspective view of a handle for a storm window insert, showing my new design;

FIGURE 2 is a front elevation thereof;

FIGURE 3 is an end view thereof;

FIGURE 4 is a top plan view thereof;

FIGURE 5 is a perspective view of a modified form of the handle for a storm window insert of FIGURE 1;

FIGURE 6 is a front elevational view of the modified form thereof;

FIGURE 7 is an end view of said modified form thereof;

FIGURE 8 is a top plan view of said modified form thereof.

This application is a continuation of my copending applications, Serial Nos. D. 65,491 and D. 65,492, filed June 6, 1961, now abandoned.

I claim:

The ornamental design for a handle for a storm window insert, as shown and described.
